US00D723748S

(12) **United States Design Patent**
Rogillio

(10) **Patent No.:** **US D723,748 S**
(45) **Date of Patent:** **** Mar. 3, 2015**

(54) **AUTOMATIC FEEDER HOUSING**(71) Applicant: **Feeder Tree, L.L.C.**, Walker, LA (US)(72) Inventor: **William Eugene Rogillio**, Walker, LA (US)(73) Assignee: **Feeder Tree, L.L.C.**, Walker, LA (US)(***) Term: **14 Years**(21) Appl. No.: **29/493,301**(22) Filed: **Jun. 6, 2014****Related U.S. Application Data**

(63) Continuation-in-part of application No. 29/452,286, filed on Apr. 15, 2013, now abandoned, which is a continuation-in-part of application No. 13/862,856, filed on Apr. 15, 2013.

(51) **LOC (10) Cl.** ..... **30-03**(52) **U.S. Cl.**USPC ..... **D30/121**(58) **Field of Classification Search**

OTHER PUBLICATIONS Brand New "Stump Feeder" from webpage at <http://forum.gon.com/showthread.php?t=415174> printed on Jul. 12, 2013.*Primary Examiner* — Susan Moon Lee(74) *Attorney, Agent, or Firm* — John B. Edel; Edel Patents LLC(57) **CLAIM**

The ornamental design for an automatic feeder housing, as shown and described.

DESCRIPTION

FIG. 1 is a front perspective view of an automatic feeder housing showing my new design;

FIG. 2 is a front elevation view thereof;

FIG. 3 is a rear elevation view thereof;

FIG. 4 is a left side elevation view thereof;

FIG. 5 is a top plan view thereof; and,

FIG. 6 is bottom plan view thereof.

The right side elevation view of the automatic feeder housing, not shown, is a mirror image of the left side elevation view thereof.

The broken line elements are not claimed.

1 Claim, 3 Drawing Sheets(56)
